CASTING MACHINE

Arthur D. Lund, Minneapolis, Minn.

Application November 9, 1932, Serial No. 641,825

7 Claims.

(CL 22—57)

This invention relates to metal casting machinery and the primary object is to provide a comparatively simple yet highly novel and efficient machine that is particularly designed for the purpose of casting primary battery grid plates, and is so constructed as to be capable of producing such plates at a high rate of speed. Further objects are to provide, in such a machine, improved metal feeding mechanisms, improved mold units and cooling system therefore, improved means for supporting and manipulating the molds, improved power transmitting devices, improved conveyor system for removing the completed grid plates, improved adjusting means for the various machine mechanisms and devices, and still other parts and features, all of which will be set forth in detail in the following specification, reference being had to the accompanying drawings, in which:

Fig. 1 is a side elevation of the machine as seen from the right, the furnace or right end of the machine being considered, for purpose of convenience, by reference, the front or forward end of the machine.

Fig. 2 is a plan view of the machine with fractional portions broken away for purpose of illustration.

Fig. 2a is an enlarged sectional detail view through one of the movable mold mounting devices.

Fig. 3 is a sectional detail view on the line 3—3 in Fig. 1.

Fig. 4 is a longitudinal sectional elevation as seen in part on the irregular line 4—4 in Fig. 2.

Fig. 5 is a transverse sectional elevation as seen on the irregular line 5—5 in Fig. 1.

Fig. 6 is a transverse sectional elevation as seen substantially on the line 6—6 in Fig. 1.

Fig. 7 is a transverse sectional elevation as seen on the line 7—7 in Fig. 2, but with the bed 36 and rams 28 in their rearmost positions.

Fig. 8 is an enlarged detail sectional elevation on the line 8—8 in Fig. 5.

Fig. 9 is a section on the line 9—9 in Fig. 8.

Figs. 10 and 11 are side elevations of the ladle operating mechanism, the same being shown in operative positions which differ from each other and also differ from that shown in Fig. 1.

Fig. 12 is a sectional elevation as seen from the right, or as on the line 12—12 in Fig. 11.

Fig. 13 is an elevation of the matrix face of the movable mold, with fractional portions broken away.

Fig. 14 is a sectional elevation through both

the movable and stationary molds, as seen on the line 14—14 in Fig. 13.

Referring to the drawings more particularly and by reference characters, 15 and 16 designate a pair of heavy channel iron side beams, connected by tie bars 17 to form a rigid and solid sub-frame support for the entire machine, said tie bars having spacer sleeves or tubes 18.

Mounted upon the forward end of the sub-frame 15—18 is a heavy cast base 19 supporting a brick lined furnace box or housing 20 adapted to be heated by gas, oil, or other fuel, in any suitable manner. The housing 20 has vents 21 for the escape of gases resulting from combustion therewithin. Supported by an annular flange 15 upon the top of the housing 20, and so as to rest therewithin, is a metal chamber or pot 22 in which the metal to be used is melted to a liquid state. The metal in this pot must be kept at a fairly constant operating level and to this end an operator supplies the pot, at suitable intervals, with material which may be conveniently kept on a shelf 23.

The operating mechanisms proper, including the molds, supports and actuators therefore, and feeding mechanisms, are carried on or disposed within a large cast housing 24, which like the base 19, is also secured and rigidly bolted on the frame 15—18.

Mounted on the forward end of the housing 24 is a hollow cast standard 25 which rigidly supports a pair of stationary molds A. This standard 25 is circuitously connected, as by pipe 26, to a chamber 27, formed in the upper front section of the housing, so that water can be circulated through both the chamber and the standard (from suitable inlets and outlets), the purpose being to provide cooling means to prevent heat emanating from the furnace 20 to have any destructive or deteriorating effect on any of the operating mechanism carried by the housing 24. This cooling system is preferably though not necessarily independent of the mold cooling system proper later to be described.

A pair of movable molds B are arranged to register and cooperate with the respective stationary molds, and are supported upon the front ends of a pair of heavy shafts or cylindrical rams 28. To effect a proper supporting connection as

between the molds B and rams 28, the latter are provided at their forward ends with rigidly secured plates or casting brackets 29 which are disposed against the back faces of the molds and are secured at spaced points thereto by bolts 30 having nuts 31. These bolts are fixed in the

molds and the nuts 31, by being drawn up tightly (see Fig. 2a), exert the desired clamping action as between the members B and 29. Before the movable molds are thus firmly secured, however, it is necessary that they be properly adjusted with respect to the stationary molds in order that accurate and uniform face contact may be had when the mold units are closed, to thus eliminate imperfect castings. To produce such adjustments I provide each plate 29 with a set of vertically and transversely spaced plugs 32, which are threaded in and extend through the plates, with abutting contact at their inner ends to engage the mold, while at their outer or rear ends they are formed to receive a wrench and also have lock nuts 33 by which they may be secured against rotation after once being set. To properly obtain this adjustment it is desirable to first loosen the members 31 and 32, to give the mold slight freedom or play, advance the rams 28 until the molds are pressed together, to effect uniform face contacts, then advance the plugs 32 until they all abut the adjacent mold surfaces, and, lastly, draw up the bolts 30, by the nuts 31, until the molds are firmly held against the several plugs 32. Lock nuts may be employed to lock the members 32 and 30 in rigid position. When the movable molds are now reciprocated they will of course always properly contact with the stationary molds.

The rams 28 are slidably secured in longitudinally disposed bearings 34 and 35 (including removable cap sections) constituting rigid portions of a large blade or bed 36. This bed has a pair of lateral integral runners 37 operating in raceways 38 in the top surface of the housing 24, the bed being slidably secured, as by retaining strips 39.

For each ram 28, and intermediate the bearings 34 and 35, the bed 36 is provided with a bearing 40, which does not necessarily have direct bearing contact with the surface of the ram, but surrounds the same, and is splined to slidably receive opposite key projections 41 of the ram. The purpose of this construction is to prevent any possible rotation or oscillation of the rams in the bearings 34 and 35, which movement, if it existed, would prevent an accurate registration of the molds upon meeting.

At their rear ends the rams 28 are provided with integral reduced extensions 42 having slidably bearing engagement with upstanding integral lugs 43 of the bed 36. Collars 44, on these extensions, engage the lugs 43 to limit forward movement of the rams 28 in the bearings 34 and 35, while similar collars 45 and springs 46 serve to yieldably hold the rams forward, or with the stop collars 44 in contact with the lugs 43. The springs 46 are of relatively heavy or stiff material so as to yield only under a considerable degree of pressure. In fact they are not intended to normally allow for a relative ram movement of more than an extremely small fraction of an inch, such as may be necessary to compensate for slight variances that may occur in the relative positions of the two movable molds. As an emergency measure, however, the springs 46 also serve to prevent a full closing of the molds should one of the grid plates only be partially discharged before the molds are closed for a succeeding operation, as a positive closing action under such circumstances might easily damage the relatively delicate matrix faces of the molds.

As will presently be described the molds B are moved forth and back by reciprocating ac-

tions imparted to the bed 36. As this action takes place, however, the mold units are not only opened and closed, to form and discharge the cast plates, but there is a cooperating mechanism for effecting a positive release of the plates from the movable molds, and this may now be set forth as follows:

When molten metal is filled into the mold cavity, C, it embraces the inner tapered ends of a series of cores 47, projecting into the cavity from the core B (Fig. 14), and the frictional contact between the core and the cooled casting tends to cause the latter to adhere to the mold B when the latter is moved to open position. This tendency is augmented or supplemented by headed push pins 48 having limited sliding movement in the mold A and which are arranged to engage the face of the casting adjacent the mold A. The pins 48 are subject to limited ejecting movements under the action of springs 49, the tension of which may be adjusted by turning threaded plugs 50 abutting such springs. It will thus be seen that as the molds open the formed casting will adhere to the movable molds. It then becomes necessary to forcibly or at least positively dislodge the castings from the molds B, and to that end each of said molds is provided with a series of knock-out pins or ejectors 51 which are slidably mounted in cages 52, secured to the outer surface of the mold. Inner reduced ends of the pins 51 extend to the matrix face of the mold, and are normally maintained flush therewith by springs 53 which act on collars 54 and thereby hold the pins with their outer or larger ends projected. The springs also abut and are removable as units with the cages 52 and pins 51.

The upper tier of knock-out pins 51 are so disposed that when the movable molds are fully opened such pins will contact with a series of adjustable stops 55 carried by a bridge member 56, in turn anchored at its ends on the housing 24. A lower tier or series of ejectors 51 similarly contact with stops 57 secured in an inner, integral partition wall 58 of the housing 24. An intermediate series of ejectors are actuated by a transversely disposed yoke bar 59 which is slidably supported on the rams 28 between the plates 29 and bearings 34. This yoke bar is so arranged that it will contact, at its ends, with adjustable stops 60 carried by lug extensions 61 at the ends of the bridge 56. Thus, as the bed 36 reaches its rearmost limit of movement, the stops 60, acting through the yoke 59, and the stops 55 and 57, will all function to simultaneously actuate all the ejectors and thus effectively discharge the cast plates from the molds B.

The required intermittent reciprocating movement to the bed 36 is imparted from a motor, M, in the following manner: the motor operates through a coupling 62 to turn a shaft 63 journaled in opposite walls of a cast case 64. Within this case the shaft has a worm 65 meshing with a worm gear 66 on a shaft 67 disposed above and at right angles to shaft 63. At its outer end the shaft 67 has a sprocket pinion 68 for driving a conveyor mechanism (later to be described), and at the opposite or machine side of the case 64 the shaft 67 has a spur pinion 69 meshing with a similar pinion 70 on a jack shaft 71 journaled in the housing 24. At its inner end the shaft 71 has a pinion 72 for driving a spur gear 73 which is fixed on an arbor shaft 74. The arbor has its ends supported in anti-friction bearings 75, and in addition to the gear 73 has secured to it a series of cams D, E, and F.

The cam D has a circular periphery except for a large angular notch 76, and the cam E has a circular periphery interrupted only by a triangular lug projection 77 having cooperating relationship with the notch 76 as will presently be explained.

A shaft 78 is journaled at its ends in bearing lugs 79, formed integral with side walls of the housing 24 and the cross partition 58, which continues in an irregular rearward and upward direction to form a more complete enclosure for the operating mechanism. It is here convenient to note that this enclosure is preferably of such a nature as to completely exclude dust and dirt, and to obtain access for oiling, repairs, etc., I have provided removable side plates 80, and an openable rear door 81 releasably secured as by devices 82.

A sleeve member 83 is trunnioned on the shaft 78, and has an upstanding integral lever arm 84, which at its upper end has a power transmitting link connection 85 with an integral depending lug extension 86 of the bed 36. This lug extension is free to reciprocate in a slotted opening 87 in the top section of the housing 24. The lever 84 is further provided, intermediate its ends, with a roller 88 for engagement with the periphery of the cam D and in the notch 76.

Laterally offset with respect to the lever arm 84 the sleeve 83 has another integral lever 89, in this instance being directed rearwardly and having a roller 90 for engagement with the under side of the peripheral surface of cam E and lug 77. The lug 77 is so spaced with respect to the notch 76 that as the former starts to engage the roller 90 the latter begins to receive the roller 88, and as the cams D and E continue to rotate the roller 90 passes completely over the lug while the roller 88 completes a reverse or inward movement through the notch. Thus during the major part of each cam rotation the lever arm 84 will be held in locked stationary position and during a short interval only will it be positively moved rearwardly, and it is this movement that is transmitted through the link 88 and lug 86 to slide the bed 36 back to open the molds.

As the molds are opened, and the plates ejected therefrom, by the kick-out mechanism already described, such plates drop down upon an endless conveyor apron 91, having a generally arcuate shape, as shown in Figs. 1 and 4, so that the plates by falling upon a downwardly sloped, moving, and flexible surface will not be injured. The apron is preferably provided with cross cleats 92, and has side chains 93 for engaging upper and lower sprockets 94 and 95 mounted, respectively, on shafts 96 and 97. The conveyor is retained in the generally arcuate position, referred to, by a series of flanged lateral rollers 98, arranged to engage the upper and lower runs, as shown. Two opposite of these rollers, namely 98a, are carried by depending levers 99 pivoted on shaft 96 and having take-up devices 100 by which the rollers 98a may be adjusted to take up slack in or tighten the conveyor. The lower shaft, 97, of the conveyor, is extended, at one end, through a bearing 101 (see Figs. 5 and 7), and at said end has a sprocket pinion 102 connected by sprocket chain 103 to the pinion 68 on shaft 67, thus providing operating power for the conveyor.

Supplementing the conveyor 91 is a second endless conveyor apron 104 passing over rollers 105 and 106 mounted, respectively, on shafts 107 and 108. The shaft 107 is driven from shaft 97 by a belt or chain 109. The shaft 108 is journaled

in bearing blocks 110, slideable in races 111, and are adjusted by devices 112 to thus regulate the tautness of the apron 104. The purpose of the apron 104 is to receive grid plates from the conveyor 91 and carry them up to a shelf 113, at the rear end of the machine, and from which shelf the plates are carried away for further treatment.

The mechanism for feeding predetermined charges of molten metal from the pot 22 to mouth extensions 114 of the molds A and B, may be described as follows: rigidly secured to the forward edge of the pot 22 are a pair of stationary angularly disposed funnels 115, the small ends of which are arranged directly over the receiving mouths, while their larger ends are adapted to receive metal from a pair of ladles 116. These ladles are fixed on a shaft 117 having a crank portion 118 adjustably secured by set screws 119 in a bell crank 120-121 journaled in the upper end of a vertical rod 122 slidably secured in bearings 123.

The arm 121 is rendered adjustable, by a device 124, with respect to a parallel arm 125, swingable on the bell crank, and having a link connection 126 with a vertical rod 127 slidable in bearings 128.

The rod 122 is connected at its lower end, by a link 129, to a bell crank lever 130 fulcrumed as at 131, in turn attached to and actuated by a telescopic connecting rod 132 which is normally held in an extended condition by a spring 133. At its rear end the rod 132 is pivoted to the arm 134 of a sleeve 135 which is journaled in a housing (24) bearing, and at its inner end has an arm 136 with a roller 137 for engagement with the periphery of the cam F. Within the sleeve 135 is rotatably mounted a shaft 138 having an arm 139 at its outer end similar to arm 134. This arm, 139, is connected by a rod 140 (similar to 132) to a bell crank lever 141, and has a spring 142 tending to at all times keep it in extended position. The lever 141 is fulcrumed, as at 143, and has a link connection 144 with the vertically slidable rod 127.

At its inner end the shaft 138 is provided with a crank arm 145 having a roller 146 for engagement with the cam F. Thus both rollers 137 and 146 travel on the peripheral surface of the cam and maintain this contact by virtue of the weight of the mechanism on the links 129 and 144. There is a difference in the movements of the rollers, at a certain point in the revolution of the cam, however, and this may be noted as follows: The roller 146 follows a path at the right, as shown in Fig. 5 (left, in Fig. 9) and consequently is influenced only by the general heart shaped contour of the cam F, as it appears in Figs. 4, 8, 10 and 11. This movement results in a uniform reciprocating action of the vertical rod 122, which in turn lifts the ladles from a submerged position in the molten metal in the pot 22 (Fig. 11) to the elevated position of the ladle as shown in Fig. 10, and, after a predetermined dwell of the ladle at this height, returns it to its lowermost position for refilling. The roller 137, on the other hand, also follows the general cam contour, but travels a path at the left of the cam as shown in Fig. 5 (right, in Fig. 9), and, at a predetermined point contacts with and passes over a triangular insert 147, in the cam, to impart a supplement lift to the rod 127. This lift occurs as the ladles reach their uppermost positions and serves to tilt and empty the ladles into the funnels 115, as indicated in Fig. 1. The rod 127 acting through adjustment 124 also determines the angular positions of the

lades when returned for refilling to the pot 22, and when it may be found necessary or desirable to vary the volume of the successive metal feeds this can be affected by adjusting the relative relationship of the arms 121 and 125 by the device 124.

It is also desirable to provide means for properly timing the tilting movement of the lades with reference to the lifting movement, and to this end the operating edge surface of the insert 147 is designed for certain adjustments. Thus, the insert 147, which is of generally triangular contour, has an arcuate inner edge which contacts with the curved bottom of a pocket 148 in the cam and is held in guiding contact therewith by a set screw 149 extending from a bracket 150 (on the cam) and into an arcuate groove 151 in the cam. To positively secure the insert in the desired adjusted position I provide clamping bolts 152 which slidably engage in slots 153 in the insert and are threaded in the cam body adjacent thereto. By adjusting the insert, as indicated by dotted lines in Fig. 8, the auxiliary roller movement thereover will be advanced or retarded with the result already noted.

When the machine is not in active use it is often desirable to run it very slowly or to change operative parts from one position to another, in order that repairs, adjustments, and observation 30 may be properly made. To accomplish this I provide a mechanism, as shown in Figs. 2 and 7. This mechanism includes a transverse shaft 154 journaled in the housing 24 and has hand wheels 155 at the opposite sides thereof. The shaft 154 is arranged to operate through bevel pinions 156 to rotate a vertical shaft 157 journaled in a housing 158 secured to housing 24. Slidably keyed on the shaft 157 is a bevel pinion 159 adapted to mesh with a bevel pinion 160 on an extension 161 of the shaft 63. The pinion 159 is vertically reciprocated by a shipper arm 162 of a rod 163, also slidably in the housing 158. This rod 163 is yieldably supported in raised position by a spring 164, thus normally keeping the pinions 159 and 160 45 out of mesh. The lower end of the rod 163 is connected by a link 165 to a bell crank lever 166 fulcrumed as at 167 and having a pedal extension 168. A second pedal lever 169, at the opposite side of the machine, is fulcrumed as at 170 50 and operates the lever 166 through connecting rod 171. It will thus be observed that by depressing either of the foot pedals 168 or 169 the bevel pinions 159 and 160 are brought into mesh, and a subsequent turning of one of the hand 55 wheels 155 will operate to rotate the shafts 161 and 63, thus revolving the arbor 14 and conveyors at any relatively low rate of speed that may be desired. Of course as soon as the foot pedal is released the spring 164 will immediately 60 disconnect the manual control mechanism.

The molds have matrix faces, as shown in Fig. 13, adapted to form a two-grid plate, which, after being completed in the mold is cut apart, trimmed, and otherwise prepared for use. As the 65 metal is poured into the downspout 114 it immediately flows into the vertical or riser column 172 from which it escapes through a series of tapered openings 173 to the interstices 174 forming the "ribs" and "wires" of the grids. At the 70 side of the mold opposite the inlet column 172 is a second riser column 175 for forming the marginal and terminal parts of the plate. This recess communicates with the grid sections proper through a vertical series of perforations 176, and 75 these perforations cooperate with perforations

173, and with the matrix interstices, to effect a uniform yet sufficiently fast flow of metal throughout the mold opening and before any appreciable hardening of the metal can take place.

The respective mold units A and B are provided with passageways for the circulation of a liquid medium to cool the mold and thereby not only prevent distortion of the mold but also eliminate damage thereto and faulty castings such as would otherwise result from high temperatures. To this end I construct the respective mold units with a series of vertical conduits drilled into the mold body proper and connected at their upper ends by certain cross conduits, while at their lower ends the vertical conduits open into manifolds 177, secured in sealing contact with the lower end edges of the molds by bolts 178. At the outer end of each gasket it is provided with an inlet 179 to which the supply conduit is attached. The inlet 179 supplies a single conduit 180 through which the cooling medium flows to a horizontal passage 181. From this passage the liquid is passed through three down tubes 182 to a chamber 183 in the manifold, to be discharged therefrom up through a tube 184 and down through a tube 185 to the discharge outlet 186 of the manifold. While supply and discharge conduits for the connections 179 and 186 are not shown, it will be understood that ordinary pipes may be used for the stationary molds, while flexible tubing or other movable conduits will be required to supply circulating fluid to the movable mold.

The particular fluid circulating arrangement, as disclosed, has been designed with a view to efficiently and effectively cooling molds of the particular design in question. Thus it will be seen that the cooling fluid initially passing up through the passage 180 will first cool the mold area adjacent the relatively heavy mass of metal in the 35 riser 175. As the fluid is then separated into three streams to pass down through the conduits 182 its cooling effect is somewhat diffused but still sufficiently effective because of the fact that the matrix face adjacent this area or zone of the 40 mold is in contact with only a very small amount of distributed metal under which circumstances there is little natural tendency to materially raise the temperature of this part of the mold block. The mold area adjacent the riser chamber 172, 50 like that adjacent the riser chamber 175, is subjected to relatively high degree of temperature because of the comparatively greater mass of molten metal therein, and to offset this condition I again restrict the fluid flow to a single stream, 55 passing it up through conduit 184 and down through conduit 185. The restriction noted so greatly accelerates the fluid flow speed that the fluid will obviously function the more efficiently to keep the adjacent mold parts at the desired 60 low temperature.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. In a casting machine, the combination including a mold, a chamber adjacent the mold for containing molten metal, a movably mounted ladle for conveying molten metal from the chamber and to a point for delivery of the metal to the mold, a rotatable cam, a ladle reciprocating mechanism having means operatively associated 70

- with the cam so as to receive movement therefrom, and a ladle tilting mechanism having a member actuated by the cam, said cam having a projection for imparting a supplemental action 5 to said tilting mechanism member.
2. In a casting machine having a motor driven power shaft, a manually operative mechanism having hand members at opposite sides of the machine, said mechanism including a normally 10 disengaged connection with the power shaft, and a pair of foot pedals, one at each side of the machine, for releasably engaging said connection, whereby either or both of said hand members may be operated to turn the power shaft.
- 15 3. An ejector mechanism for a mold of a casting machine comprising, a cage secured in the back of the mold adjacent a perforation through the latter, an ejector pin extending through both ends of the cage and at one end into said perforation, a spring within the cage for action at one end upon the pin, said cage having an integral inwardly formed flange forming a substantially closed end for the cage to abut the other end of the spring, thereby securing the 20 cage, pin, and spring in one compact removable unit.
4. A grid casting mold block having a metal receiving throat at one side thereof, a pair of spaced riser chambers, one of which is adjacent to said 25 throat, and a matrix face connecting said risers, an initial fluid circulating passage extending through the mold body adjacent the riser chamber remote from the metal receiving throat, a series of spaced passages extending through the mold adjacent the matrix face and adapted to divide and circulate fluid received from the first mentioned passage, and a third passage in the mold arranged to receive, in a reunited flow, fluid 30 from the second mentioned passages and circulate it at increased speed through the mold part having the riser chamber which is adjacent the metal receiving throat.
5. In a casting machine, the combination including a mold, a chamber adjacent the mold for containing molten metal, a ladle for conveying molten metal from the chamber and to a point for delivery of the metal to the mold, cam actuated means for mounting, raising, and lowering the 10 ladle, means associated with the cam for tilting the ladle when in its raised position, and means for adjusting the tilting means to thereby adjust the timing of the tilting action.
6. In a casting machine, the combination including a mold, a chamber adjacent the mold for containing molten metal, a ladle for conveying molten metal from the chamber and to a point for delivery of the metal to the mold, cam actuated means for mounting, raising and lowering the 15 ladle, means associated with the cam and operative therewith for tilting the ladle when in its raised position, and means for adjusting the speed of the ladle tilting movement.
7. In a casting machine, the combination including a mold, a chamber adjacent the mold for containing molten metal, a funnel fixed with respect to and above the mold, a ladle for conveying molten metal from the chamber to the funnel, means for mounting the ladle and for moving it 20 from the metal receiving position in the chamber to a discharge position with respect to the receiving end of the funnel, and means for angularly adjusting the ladle when in its metal receiving position in the chamber to thereby control the 25 volume of metal passing from the chamber into the ladle.

ARTHUR D. LUND.
